John Ruben Tacey

UNITED STATES PATENT OFFICE.

JOHN RUBEN TACEY, OF WINNIPEG, MANITOBA, CANADA.

HEAT-RADIATOR.

SPECIFICATION forming part of Letters Patent No. 395,013, dated December 25, 1888.

Application filed December 7, 1887. Serial No. 257,248. (No model.) Patented in Canada February 13, 1888, No. 28,527.

To all whom it may concern:

Be it known that I, JOHN RUBEN TACEY, of the city of Winnipeg, in the county of Selkirk, Province of Manitoba, in the Dominion of Canada, have invented certain new and useful Improvements in Heat-Radiators, (for which I have obtained a patent in Canada, No. 28,527, bearing date February 13, 1888,) of which the following is a specification.

10 My invention relates to improvements in heating-radiators, draft-regulators, and self-cleaning fuel-savers.

15 My object is to give a greater heating-power with less fuel, also, being a self-cleaner, to save cost and danger from fire. I attain this object by mechanism illustrated in the accompanying drawings, in which—

20 Figure 1 is an elevation of heat-radiator; Fig. 2, a vertical section of cone, revolving pipe, and radiator; Fig. 3, cone and damper-pipe with cleaning-rod.

25 The first part of my invention consists of a cone, A, constructed downward with opening in bottom at I, placed inside of radiator B, giving radiation of heat; second, of an inner pipe, M, so placed that when handle E is turned horizontally to the left it revolves with

draft-hole cut in side at C and meets hole in outer pipe, N, at D. When handle is reversed, it closes direct draft and causes smoke to ascend and descend to the bottom of cone at F, and out of inner pipe, M, which causes radiation of heat and saving of fuel. 30

My self-cleaner is a vertical rod, G, attached to cross-bar H, with arrow-shaped bottom at 35 mouth of cone, and the rod extending through small hole at I, scraping sides of cone, keeping it free from soot and making it a self-cleaner.

What I claim as my invention, and desire to 40 secure by Letters Patent, is—

The combination of outside casing, B, cone A, with opening at I, inner pipe, M, having hole at C, outer pipe, N, having hole at D, handle E in horizontal slot, cross-bar H, and 45 vertical rod G, having arrow-shaped bottom, substantially as and for the purposes hereinbefore set forth.

Winnipeg, county of Selkirk, Province of Manitoba, May 2, 1888.

JOHN RUBEN TACEY.
